HYDROMECHANICAL PRESS

Howard F. MacMillin and Don C. Youngblood,
Mount Gilead, Ohio, assignors, by mesne assignments,
to The Hydraulic Press Corporation,
Inc., Wilmington, Del., a corporation of Delaware

Application May 25, 1934, Serial No. 727,550

3 Claims. (Cl. 100—71)

This invention relates to presses, and, in particular, to hydraulic presses having mechanical connections for the application of hydraulic power.

5 One object of our invention is to provide a hydromechanical press wherein the power is produced by hydraulic means but applied by mechanical connections.

Another object is to provide a hydromechanical press having a horizontally-disposed hydraulic cylinder-and-piston assembly arranged to move a vertically-disposed platen, as through toggle or crank connections therebetween.

Another object is to provide a hydromechanical press wherein a hydraulic ram moving in one direction is caused to move a platen in a direction perpendicular thereto.

Another object is to provide a hydraulic press having mechanical means for adjusting the maximum position reached by the platen during operation.

Another object is to provide a hydromechanical press wherein an adjustable wedge is used to regulate the position reached by the platen in its motion.

25 Another object is to provide a hydraulic press having a hydraulic cushion in one of the pressing surfaces, this cushion embodying means for stopping or reversing the action of the press when the pressure upon the cushion reaches a predetermined amount.

Another object is to provide a hydromechanical press with a hydraulic cushion in one of the pressing surfaces thereof, together with an electrical switch actuated by the pressure undergone by the cushion in such a manner that the switch is operated to energize an electrical circuit which in turn changes the motion of the press when the pressure upon the cushion exceeds a predetermined amount.

40 Another object is to provide a hydromechanical press having electromechanical control means for permitting the press to be manually controlled, pressure-controlled, or position-controlled in either a semi-automatic or completely-automatic manner.

In the drawings:

Figure 1 is a front elevation, partly in section, of the hydromechanical press of my invention, 50 showing the control valve in longitudinal section, and in a neutral position;

Figure 2 is a longitudinal section through the control valve shown in Figure 1, but with the parts arranged in the "forward" position so as 55 to produce a down-stroke of the platen;

Figure 3 is a longitudinal section through the control valve shown in Figures 1 and 2, but with the parts in a "reverse" position to produce an upward stroke of the platen;

Figure 4 is a side elevation of the press shown 5 in Figure 1, the control valve being omitted to conserve space;

Figure 5 is a vertical section along the line 5—5 of Figure 1;

Figure 6 is a wiring diagram of the control 10 circuit for the press of my invention;

Figure 7 is an enlarged detail view showing the crank shaft and solenoid connections.

General construction of the press

15

Referring to the drawings in detail, Figure 1 shows a press having a base 1 and a top piece 2 interconnected by side members 3 through the agency of the strain rods 4, on which are threaded the nuts 5. Secured to the side members 3, as 20 by the screws 6, are the retaining members 7. The latter are arranged adjacent to the guide portions 8, serving to receive the press platen 9 and guide it in its vertical reciprocation. The platen 9, on its lower surface, is provided with a slot 10 adapted to hold a die, work pieces or other suitable devices. Journalized in the bearings 11 in the upper part of the platen 9 is a cross shaft 12 (Figures 1 and 5), to which a link member 13 is pivotally secured.

The opposite end of the link member 13 is pivotally mounted upon the cross shaft 14, which is journalized in the bearings 15 on the yoke portion 16 of the hydraulic cylinder 17. The cross shaft 14 also pivotally supports the link members 18, whose upper ends are pivotally mounted upon the cross shaft 19. The ends of the cross shaft 19 are journalized in the bearings 20, arranged within a movable anchor block 21, which in turn is reciprocable along vertical guide

portions 22 on the side members 3 and held in position by the side plates 23, bolted thereto by the screws 24 (Figure 1). The upper part of the anchor block 21 is threaded to receive the vertical rods 25. The latter pass upwardly through the top member 2 and are provided with coil springs 26, held in place by the threaded nuts 27. Accordingly, the anchor block 21 is yieldably urged upward against the press top member 2 by the springs 26. The anchor block 21 likewise contains a stud screw 28, which is received within the bore 29 of the top member 2. The latter is hollow to provide a tank for the fluid used to operate the various hydraulic mechanisms of the press.

30

35

40

45

50

55

To adjust the position of the anchor block 21, a movable wedge 30 is provided (Figure 5), and interposed between the anchor block 21 and the lower surface of the press top member 2. When this wedge is moved horizontally, as by the hand wheel 31 upon the threaded stud shaft 32, the wedge 30 moves in or out and consequently moves the anchor block 21 up or down. This adjustment of the position of the anchor block 21 regulates the lowest position of the platen 9 during its working strokes.

The hydraulic cylinder 17 contains a piston 33, whose piston rod 34 is threaded into a swivel block 35, arranged to swivel around the shaft 36. The latter is mounted upon a bracket 37, secured to the side members 3 of the press (Figure 5). To prevent leakage between the piston rod 34 and the cylinder 17, through which it passes, an adjustable gland 38 is provided, and arranged to compress a packing 39, whereby such leakage is prevented.

The base portion 1 of the press contains a cushion block 40 reciprocable in a bore 41 against the pressure of the coil spring 42. The lower portion of the cushion block 40 serves as a hydraulic piston, and the space between it and the bottom of the bore 41 contains fluid, such as oil. The leakage of this fluid is prevented by the adjustable gland 43 adapted to compress the packing 44 around the cushion member 40.

A pipe 45 leads from the bottom of the bore 41 to the switch-actuating cylinder 96. Within this cylinder 96 is a piston 95 reciprocable against the urge of a coil spring 97. The tension of the spring 97 is adjusted by the threaded plug 98, through which passes the piston rod 94. The latter is adapted to engage the switch knob 93 of an electrical switch 90, whose connections will be hereinafter more fully disclosed. Thus when the platen 9 causes pressure to be exerted upon the cushion 40, the latter will transmit this pressure by the fluid within the bore 41 to the switch cylinder 96. When this pressure becomes sufficient to overcome the resistance of the spring 97, the piston rod 94 will engage the knob 93 and throw the switch 90.

Controlling devices for the press

The press is arranged so that it may be operated in a variety of ways. First of all, it may be operated by hand, so that each motion of the platen 9 downward or upward is controlled by a hand lever shifted by the operator.

The press may likewise be controlled for "semi-automatic operation", whereby the plunger performs a working stroke, reverses itself, proceeds to the top of its return stroke and automatically comes to rest; or else it may be controlled for "completely automatic operation", whereby the plunger performs a working stroke, reverses itself, returns to its starting position, performs another working stroke, reverses itself again, and so on, repeating the working strokes indefinitely until stopped by the operator. The reversal of the platen may be either "pressure controlled" so as to occur when the pressure exerted by the platen reaches a predetermined amount; or "position-controlled", as when the platen reaches a predetermined position. These results are obtained by the control devices shown in Figures 1 and 4, and by the electrical circuit shown in Figure 6.

The top member 2 and the base member 1 of the press are provided with lugs 130, which are bored to permit the vertical reciprocation of the

control rod 131 therethrough. The latter is provided with a spring 132 held in position by a collar 133. The reciprocation of the control rod 131 is limited by the collar 134 mounted on the lower end thereof. An adjustable collar 135 is also placed upon by the control rod 131, and is adapted to be engaged by the contact sleeve 136 of the arm 137 bolted to the extension 150 of the platen 9. (Figure 4.)

The platen 9 is also provided with an arm 138 having a contact sleeve 139, adapted to slide up and down along the switch rod 103 (Figure 4) and engage an adjustable collar 140 thereon. The switch rod 103 reciprocates vertically in bored lugs 141 and 142, attached respectively to the top member 2 and the side member 3 of the press. The switch rod 103 is surrounded by the coil spring 143 held in place by the threaded cap 144. The reciprocation of the switch rod 103 is limited by the collar 145, engaging a lug 141 on the top member 2 of the press (Figure 4).

The control rod 131 is provided with an adjustable collar 120 which serves to engage the knob 121 of a switch 117 (Figure 4), when the upward limit of the platen is reached. Similarly, the switch rod 103 is provided with an adjustable collar 102 adapted to engage the knob 101 of a switch 91 when the lowermost position of the platen 9 is reached.

The control rod 131 is also provided with a collar 146, engaged by the crank 147, mounted upon the crankshaft 148. The latter is supported in the lugs 149 on the side member 3 of the press, and is provided with a hand lever 151, by which the crankshaft 148 may be turned. (Figures 1 and 4.)

The opposite end of the crankshaft 148 is provided with a lever 152, which is connected by the link 153 to a yoke 154 on the end of the armature shaft 155 of the solenoid 156. Accordingly, when the solenoid 156 is energized, the crankshaft 148 is rotated. The coil spring 157 is arranged between a hook 158 on the side member 3 and a lever 159, mounted upon the shaft 148 and extending in an opposite direction from the lever 152 (Figures 4 and 7).

Also secured to the crankshaft 148 is a lever 160, which engages a link 161, to the opposite end of which is attached the valve connecting rod 162 (Figure 1). The latter passes through the end walls of valve casing 163, within which reciprocates the valve member, generally designated 164.

The valve member 164 is provided with a neck 165, upon which spaced heads 166, 167 and 168 are arranged. The valve neck 165 also contains a bored passage 169 so as to maintain communication between opposite sides of the valve head 167. The valve casing 163 is provided on one side with the spaced ports 170, 171, and 172, all of these being connected to the discharge pipe 174, leading to the tank 175 of a hydraulic pump 176. The pressure line 177 from the hydraulic pump 176 enters the valve casing 163 by the port 173, whereas the suction line 178 proceeds downwardly into the tank 175.

The valve casing 163 also contains ports 179 and 180, from which pass the pipes 181 and 182. These proceed respectively to the opposite ends of the hydraulic cylinder 17 (Figure 5). Thus when the valve member 164 is set, as shown in Figure 1, the pump by-passes its fluid and the press remains in a neutral position. In the Figure 2 arrangement, pressure fluid passes through the pipe 181 into the space in front of the piston head 33, causing the cylinder 17 to recipro-

cate and execute a downward motion of the platen 9 (Figure 5). Conversely, when the valve member 164 is arranged as shown in Figure 3, pressure fluid will enter the space behind the piston head 33 by way of the pipe 182, causing the cylinder 17 to reciprocate rearwardly and draw the platen 9 upward. Thus the operation of the valve member 164 may be controlled manually by the hand lever 151, or else electrically by the action of the solenoid 156.

Electrical control circuit

The electrical circuit whereby the solenoid 156 and the electrical accessories of the press are connected or disconnected is shown in Figure 6. Electrical energy for the operation of the circuit is received from the power lines 55 and 56 and passes to the magnetic switch, generally designated 50. The magnetic switch 50 is a two-pole normally-open main switch, which is provided with switch arms 59 and 60, adapted to engage switch points 61 and 62, to which the power lines 55 and 56 are respectively connected. The switch arms 59 and 60 are normally kept out of contact with the switch points 61 and 62 by being mounted upon the shaft 63, which is rotated in the direction of the arrow by the spring 53 attached to the arm 52 and anchored to the hook 54. The solenoid 156 is energized by the lines 57 and 58 coming from the switch arms 59 and 60.

The magnetic switch 50 is rotated in the opposite direction to the arrow and thereby closed by an electrical pilot circuit connected across the lines 55 and 56. This pilot circuit comprises three branches 65, 66, and 67, having a common circuit portion 68, connecting each branch to the power line 56. The branches 65, 66 and 67 also have a common circuit portion 69 connecting them to the power line 55. The circuit 68 includes the holding coil 71, which, when energized, serves to close the switch 50, this action being performed by its attracting the armature 72 attached to the switch shaft 63, as at 73. The opposite end of the armature 72 carries a normally-open contactor bar 74. When the holding coil 71 is energized, the contactor bar 74 engages the contact arms 75 and 76, thus connecting the line 65 with the line 69, and completing the pilot circuit through the former.

The line 68 contains the manually operated switch 70 (Figure 6), whereby the holding coil 71 may be permanently de-energized. The line 68 contains a branch line 79, leading to a normally-closed emergency reverse push button switch 80, from the opposite side of which leads the line 81 to one arm 84 of the double-pole double-throw switch 83. To the opposite arm 85 thereof is attached the line 82 leading to the contact arm 75 of the magnetic switch 50.

The double-pole double-throw switch 83 contains a pair of switch points 86 and 87 which, when engaged by the switch arms 84 and 85, will close the circuit through the normally-closed pressure-responsive switch 90. Conversely, when the arms 84 and 85 engage the opposite contact points 88 and 89 of the double-throw switch 83, the circuit will be closed through the normally-closed lower position switch 91 operated by the extension 150 of the platen 9.

Assuming the switch arms 84 and 85 to be engaging the switch points 86 and 87, when the pressure within the chamber 41 beneath the cushion 40 exceeds a predetermined amount and 75 throws the pressure reverse switch 90 by means

of the pressure cylinder 96 and the piston rod 94, the latter disconnects the pilot circuit and de-energizes the holding coil 71 of the magnetic switch 50, thereby de-energizing the solenoid 156. The spring 157 then causes the valve member 164 to move to its Figure 3 position, thus starting an upward stroke of the platen.

If, on the other hand, the arms 84 and 85 of the double-throw switch 83 are closed upon the contact points 88 and 89, the platen-operated lower position switch 91, which is normally closed, will be thrown open when the switch rod 103 is moved downward by the platen until the collar 102 engages the switch knob 101 and opens the switch. This again de-energizes the holding coil 71 of the magnetic switch 50, and accordingly de-energizes the solenoid 156, and thus in a similar manner to that previously described, causes the valve member 164 to be shifted to its reverse position (Figure 3) under the action of the spring 157. Thus by throwing the double-throw switch 83 in one direction, the press becomes reversible when a predetermined pressure is reached, whereas by throwing it in the opposite direction the press becomes reversible when a predetermined position is reached.

When the holding coil 71 has been once energized, however, and the contactor bar 74 caused to engage the contact arms 75 and 76, the holding coil 71 will be maintained in an energized condition through the lines 82 and 69, together with either of the circuits previously described, until either the emergency reverse switch 80, the pressure reverse switch 90, or the lower position reverse switch 91 is opened.

The holding coil 71 is connected by the lines 68 and 79 through the push button starter switch 112 and the lines 113 and 69 to the power line 55, previously mentioned. Assuming that the magnetic switch 50 is open (Figure 6) and the various circuits de-energized, the closing of the manually operated push button starter switch 112 energizes the pilot circuit through the lines 68, 79, 113, and 69. This energizes the holding coil 71 and closes the magnetic switch 50. The contactor bar 74 then engages the contact arms 75 and 76, maintaining the holding coil 71 in an energized condition even when the push button starting switch 112 is released and opened.

Under the action of the above described circuits, the platen will move downward and engage the dies and work pieces, reversing itself when the predetermined pressure or the predetermined position is reached, according to the setting of the double-throw switch 83. The platen then returns to its topmost position and comes to rest. This mode of operation is termed "semi-automatic operation".

When "completely automatic operation" is desired, so that the platen immediately starts another downward stroke after reaching its topmost position, the circuit shown at the bottom of Figure 6 comes into play. This circuit includes the manually-operated switch 115 connected on one side to the line 68 by the line 67 and on the other side by the line 116, running to the upper position switch 117. The latter is a normally-open switch which is closed when the platen pushes the control rod 131 upward and causes the collar 120 to engage the switch knob 121 and close the switch 117. This again energizes the holding coil 71 of the magnetic switch 50, thus energizing the solenoid 156, shifting the valve member 164 to its "working stroke" position (Figure 2), and causing a downward stroke 75

of the platen to take place. The platen will then move downward, release the upper position switch 117, and will continue its movement until it causes either the pressure control switch 90 or the position-controlled switch 91 to be thrown, thereby de-energizing the solenoid 156 and reversing the action of the press. In this manner, the press is caused to repeat its working strokes indefinitely until the manual switch 115 is opened.

10 The reversal of the platen at the end of a working stroke, either at "position" limit or at "pressure" limit, together with an electromechanical circuit for operating the press in a "semi-automatic" or "completely-automatic" manner, has been disclosed in the present specification.

15 It will be understood that we desire to comprehend within our invention such modifications as may be necessary to adapt it to varying conditions and uses.

20 Having thus fully described our invention, what we claim as new and desire to secure by Letters Patent is:

25 1. In combination in a press, a movable platen, a hydraulic cylinder-and-piston assembly adapted to move said platen, a cushion adapted to be actuated by said platen, and means for causing the reversal of motion of said platen responsive to the attainment of a predetermined pressure upon said cushion, said reversing means comprising a member adapted to reverse the movement of a fluid, electrical means adapted to shift said member to reversing position, and a pressure-responsive switch operatively connected to said cushion and adapted to be operated to 30 control the actuation of said electrical means in response to the attainment of said predetermined pressure upon said cushion.

35 2. In combination in a press, a movable platen, a hydraulic cylinder-and-piston assembly adapted to move said platen, a cushion adapted to be

40 actuated by said platen, a member adapted to reverse the movement of a fluid, electrical means adapted to shift said member to a reversing position, a switch adapted when operated to energize said electrical means to shift said member to a reversing position, and a hydraulic plunger connected to said cushion and adapted to operate said switch to energize said electrical means and shift said member to reversing position in response to the attainment of a predetermined pressure upon said cushion whereby to reverse the direction of travel of said platen in response to its causing a predetermined pressure to be exerted upon said cushion.

45 3. In combination in a press, a movable platen, a source of pressure fluid, a hydraulic cylinder-and-piston assembly adapted to move said platen, a member adapted to reverse the movement of the fluid, a cushion adapted to be actuated by said platen, between said source and said assembly, electrical means adapted to shift said member to a reversing position, a switch adapted when operated to energize said electrical means to shift said member to a reversing position, and a hydraulic plunger connected to said cushion and having yielding means associated therewith arranged to oppose the shifting of said plunger when acted upon by the pressure fluid transmitted thereto from said cushion, said plunger being adapted to operate said switch to energize 50 said electrical means and shift said member to reversing position in response to the attainment of a predetermined pressure in said cushion sufficient to overcome the opposition of said yielding means whereby to reverse the direction of travel of said platen in response to its causing a predetermined pressure to be exerted upon said cushion.

HOWARD F. MACMILLIN.
